UNITED STATES PATENT OFFICE.

HENRY A. SCHMIDT, OF TORONTO, ONTARIO, CANADA.

BRACELET AND LINK THEREFOR.

Application filed October 18, 1921. Serial No. 503,516.

To all whom it may concern:

Be it known that I, HENRY A. SCHMIDT, a citizen of the United States, residing at Toronto, Ontario, Canada, have invented 5 certain new and useful Improvements in Bracelets and Links Therefor, of which the following is a specification.

The present invention relates to bracelets and more particularly to bracelets of the 10 flexible flat-link type, wherein the links are so connected as to yield radially to permit the bracelet to adapt itself to the arm of the wearer.

Among the objections heretofore found in 15 bracelets of this type is deficient flexibility, multiplicity of parts, a plurality of solder points for each link, complexity of construction and cost of manufacture. In general, the purpose of this invention is to overcome 20 these and other objections and provide a simple, thoroughly flexible bracelet in which the links each comprise a single piece so shaped and disposed as to interlock with each other, each link having but one solder point, and the whole being producible at a 25 low cost.

In order to more clearly disclose the construction, operation, and use of the invention, reference should be had to the accompanying drawings forming part of the present application. Throughout the several figures of the drawings like reference characters designate the same parts in the several views.

35 In the drawings:

Fig. 1 is a top plan view of several links, connected together;

Fig. 2 is a top plan view of one of the link blanks, enlarged;

40 Fig. 3 is a cross section on line 3—3 of Fig. 2, and

Fig. 4 is a central, vertical, longitudinal cross section through Fig. 1.

It is understood, of course, that all of the 45 views are greatly enlarged in order to clearly set forth the details of construction. Preferably, of course, the bracelet is made of gold, platinum, or other suitable precious metal and, if desired, may be set with diamonds or 50 other suitable gems as more particularly indicated in Fig. 1.

In the preferred method of manufacture, a suitable piece of the metal is stamped and punched to form the blank shown in Fig. 2.

55 This may be done either as a single operation or by several. It is obvious, that the

openings for the gem settings may be omitted if desired and the metal left either plane or ornamented in those parts. The blank, so made, comprises a top member 1 having a tongue receiving seat or recess 2 with an ear 3 at each end thereof, a bottom member 4 having a tongue 5 adapted to be seated in recess 2, as will later appear, and a connecting web 6 depressed slightly below the plane of both members and provided with two similar parallel tongue receiving openings 7 and an intermediate strip 8, the whole web being adapted to be folded upon itself so that the two openings are exactly 70 superposed one upon the other to constitute in reality, a single opening through the folded web, as more clearly shown in Fig. 4. The shoulder formed by depressing the web below the bottom member is beveled as at 9, 75 and the angle made by folding the tongue 5 at its junction with bottom member 4 for insertion through the superposed or aligned openings 7, is similarly beveled at 10 so that the two oppositely beveled surfaces are adjacent and in position to cooperate when the parts are assembled, as clearly shown in Fig. 4. The web 8 which is rectangular in cross section in the flat blank, becomes substantially semi-circular in lateral cross-section when it is folded about its longitudinal axis in the folding step by which the lower member is brought beneath the upper.

In making a bracelet from a series of these link-blanks, each blank is folded as in Fig. 4, 90 so that the two openings 7 become superposed or aligned at one side or edge of the top member and in position to freely receive the tongue 5 which has been previously bent up from the bottom member 4 after the bottom 95 member has been folded over beneath the top member 1, as in Fig. 4. In that, the final, position, the tongue end lies in recess 2, between the ears 3, and is secured there by solder 11, that being the only solder connection in each link. Of course, the width of each opening 7 is slightly greater than the thickness of tongue 5 to allow the tongue 5 to have sufficient play in these openings to prevent binding and insure full flexibility. Likewise, the bevels 9 and 10, being on the inner circumference of the bracelet permit the links to be rocked toward each other at these points, for flexing of the bracelet.

110 If desired, the top member 1 may be cut or punched out as at 12 to form a seat for

a suitable gem 13, and the other member may be punched out as at 14 to provide access to the under face of the gem, or, if desired, simply to lighten the bracelet and, at the same time reduce the quantity of valuable metal required.

As will be seen, a single simple stamping will produce each link, and the two successive simple bends place the tongue of each link in position to be passed through the openings of the link preceding it, a single solder point securing the tongue in its recess.

The construction, while simple, inexpensive, and efficient, is strong and durable, practically the entire strain falling upon the web 8, doubled over, and the tongue 5, at the point where the tongue can best support the strain—where it is bent at an angle from the bottom member 4. Also, such disposition of the parts allows of greatest possible flexibility, the web 8 acting, practically, as a pivot about which tongue 5 and its link rock, as will be clear.

It is thought that the construction, operation and use of the invention will be clear from the preceding detailed description.

Changes may be made in the construction, arrangement and disposition of the several parts of the invention within the scope of the claims, without departing from the field of the invention, and it is meant to include all such within this application wherein only a preferred form has been disclosed.

Having thus described my invention, what I claim and desire to secure by Letters Patent is:

1. A bracelet blank comprising a top member having a tongue receiving recess in one edge, a bottom member adapted to be folded to a position directly beneath the top member, a tongue carried by said bottom member and adapted to be seated in the aforesaid recess, means for securing said tongue in said recess, and a web connecting said top and bottom members and provided with tongue receiving openings.

2. A bracelet blank comprising a top member having a shoulder, a bottom member adapted to be folded directly beneath said top member to engage the aforesaid shoulder and space said members apart, a tongue carried by said bottom member, and a web connecting said members and provided with tongue receiving openings, said web having a strip adapted to be engaged by said tongue and to lie between said members in their superposed relation.

3. A bracelet blank comprising a top member having a shoulder and also having a tongue receiving recess, a bottom member adapted to be folded directly beneath said top member to engage the aforesaid shoulder and space said members apart, a tongue carried by said bottom member, and adapted to be seated in said recess, means for securing said tongue in said recess, and a web connecting said members and provided with tongue receiving openings, said web having a strip adapted to be engaged by said tongue and to lie between said members in the superposed position.

4. A plurality of links each comprising a top member and a bottom member integrally connected, said members being adapted to be superposed one upon the other, a connecting element carried by each link and adapted to lie between the free ends of the members of an adjacent link to space said members and having tongue receiving openings therethrough, a tongue carried by the lower member of each link and extended through such tongue receiving openings of an adjacent link, and means for securing said tongue in the adjacent link.

5. A bracelet blank comprising a top and a bottom member integrally connected and adapted to be superposed one above the other, spacing shoulders whereby said members may be maintained in spaced relation adjacent the edge at which they are connected, a connecting element carried by each link and adapted to lie between and space the free ends of the upper and lower members when in superposed relation, and a tongue carried by said bottom member and engaging said connecting element.

6. A plurality of links each comprising a top member and a bottom member integrally connected, said members being adapted to be superposed one above the other, means for spacing said members in superposed relation, a connecting element carried by each link and adapted to lie between the spaced members of an adjacent link, a tongue carried by the latter link and engaging said element, the edges of the lower member being beveled, where adjacent, to prevent binding of one upon the other.

Signed at Toronto, Canada, this 12th day of October, 1921.

HENRY A. SCHMIDT.

Witness:

F. A. BOHNE.
